UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR-TRUCK.

1,000,480.

Specification of Letters Patent. Patented Aug. 15, 1911.

Application filed May 19, 1909. Serial No. 496,906.

To all whom it may concern: .

Be it known that I, WALTER S. ADAMS, a citizen of the United States, and a resident of the city and county of Philadelphia and State of Pennsylvania, have invented a new and useful Improvement in Car-Trucks, of which the following is a specification.

The object of my invention is to provide a car truck which will be smooth and easy-
10 riding when operated at high speed such as sixty or seventy miles an hour. This object is accomplished by my invention, one embodiment of which is hereinafter set forth.

For a more particular description of my invention, reference is to be had to the accompanying drawings, forming a part hereof, in which:

Figure 1 is a side elevation of a truck provided with my improvements. For convenience of illustration in this and the two following figures, the old and well known parts of the truck are shown in dotted lines. Fig. 2 is a sectional view taken on the line 2—2 of Fig. 1, looking in the direction of the arrows. Fig. 3 is a sectional view taken on the line 3—3 of Fig. 2, looking in the direction of the arrows. Fig. 4 is a perspective view of a band for an elliptic spring. Fig. 5 is a perspective view of a spring plank and portions of elliptic springs mounted thereon. Fig. 6 is a perspective view of a plate which is adapted to be placed between a spring plank and the bands of a pair of elliptic springs. Fig. 7 is a plan view of the structures shown in Fig. 5. Fig. 8 shows a T-bolt. Figs. 9 and 10 are cross sections showing the spring plank and elliptic springs together with the connecting parts. Fig. 11 is a sectional view taken on the line 11—11 of Fig. 7, looking in the direction of the arrows. Fig. 12 is a plan view of a spring cap. Fig. 13 is a sectional view taken on the line 13—13 of Fig. 12, looking in the direction of the arrows. Fig. 14 is a side elevation of this cap. Fig. 15 is a longitudinal section thereof. Fig. 16 is a side elevation of one of the supports or saddles of the sand plank. Fig. 17 is a longitudinal section of the same, taken on the line 17—17 of Fig. 16. Fig. 18 is a side elevation of a portion of an equalizing bar. Fig. 19 is a plan view of the same. Figs. 20, 21 and 22 are sectional views on the lines 20—20, 21—21 and 22—22, respectively, of

Fig. 18, looking in the direction of the arrows.

Throughout the various views of the drawing similar reference characters designate similar parts.

My improved truck 1 is provided with the usual wheels 2, axles 3, axle boxes 4, pedestal 5, axle box springs 6, top chord 7, tie bars 8, together with the other usual parts which are characteristic of the type of truck shown. Each top chord 7 has near each pedestal 5, a link 9 which is bent so as to engage three sides of the top chord 7 and hang with substantial rigidity therefrom. Near the lower edge of the said top chord 7, each link is bent outwardly and downwardly and a little lower it is bent so as to stand vertically and finally its lower ends are turned slightly upwardly and inwardly in the conventional manner to engage a spring seat 10, which is supported as shown on the lower ends of each link 9. The seat 10 may be given any suitable shape but is preferably made as shown.

A suitable coil spring 11 is carried by the seat 10, and is surmounted by a cap 12 that has guiding lugs 13 which are adapted to rub against the vertical parts of the link 9, in which it is placed and this cap 12 also has a journal bar 14 adapted to receive the rounded ends of an equalizing bar 15. The equalizing bar 15 is not straight, but is bent in a manner similar to the equalizing bar of any ordinary Master Car Builders' truck and is preferably made as shown; that is with a curved upward surface at its center as shown in Fig. 20, a rectangular cross section between its ends and center as shown in Fig. 21, and a circular cross section at its ends as shown in Fig. 22, which circular ends are adapted to rest on and fit the journal bearings 14 of the caps 12.

Near the center portion of equalizing bars 15 are fixed small angle plates 16 and these are held by means of suitable cap screws 17, which are adapted to rub against adjacent saddles 18, that rest on the circular curved portions of the equalizing bars 15 and carry the angle metal bars 19, which taken together compose the spring plank 20. The saddles 18 are provided with suitable lugs 21 adapted to enter corresponding recesses in the bars 19 and the bars 19 are fixed to the saddles 18 by means of suitable bolts 22,

The spring plank 20 carries plates 23 on which rest bands 24 of the elliptic springs 25, which are bolted and secured to said plates 23 by means of T-bolts 26 and the plates 23 are fixed to the spring plank 20, by means of suitable bolts 27. The bolster is carried from the springs 25 and between transoms in the conventional manner and supports a car body in the usual way.

- 10 When my improved truck made as above described is in use, the weight of the car body and its contents is transmitted through the bolster to the elliptic springs 25, which transmit the load to the spring plank 20, 15 from thence it is distributed between equalizing bars 15, through the saddle 18 and from thence is carried to the caps 12, springs 11, seat 10 and links 9 to the top chord 7 of the truck frame.
- 20 Any tendency of the bolster to swing transversely of the truck is provided for by the saddles 18, which ride on equalizing bars 15 and the caps 12 which carry said equalizing bars and permit an angular 25 movement of said equalizing bars, but as this swinging of the equalizing bars elevates the car body, the tendency to swing is greatly reduced, and the swinging when once started does not last. The links 9 do 30 not swing at all, as they are substantially rigid with the top chord 7.

While I have shown and described one embodiment of my invention, it is obvious that it is not restricted thereto, but is broad 35 enough to cover all structures that come within the scope of the annexed claims.

What I claim is:—

1. In a car truck having a frame with side bars, springs suspended from the side bars, a cross bolster, longitudinally extending equalizing bars, and means for pivotally supporting the bolster on the equalizing bars and the latter on said springs.
2. In a car truck having a frame with side bars, links pendant from the side bars and rigidly connected therewith, springs supported by said links, a cross bolster, longitudinally extending equalizing bars, and means for pivotally supporting the bolster on the equalizing bars, and the latter on said springs.
3. In a truck of the class described, top chords, links hung from said chords, springs carried by said links, caps on said springs, equalizing bars resting on said caps and a spring plank carried by said equalizing bars.
4. In a truck of the class described, top chords, links hung substantially rigid from said chords, springs carried by said links, springs on said seats, caps on said springs with journal bearings therein, equalizing bars with offset portions journaled in said caps, saddles carried by said equalizing bars and a spring plank carried by said saddles.
5. In a truck of the class described, top

chords, spring links suspended from said chords, spring seats supported by said links, springs on said seats, caps on said springs with journal bearings and guides, equalizing bars with offset portions journaled in said caps and rounded center portions, saddles carried by said rounded center portions and a spring plank carried by said saddles.

6. In a truck of the class described, a spring plank composed of parallel angle bars, a plate bolted to said bars, elliptic springs resting on said plate and T-bolts fixing said springs to said plate.

7. In a truck of the class described, a saddle adapted to rest on said equalizing bars and provided with an upwardly extending lug adapted to enter a corresponding recess in a spring plank.

8. In a truck of the class described, a cap for coil springs provided with a journal bearing and lugs adapted to engage a spring link.

9. In a truck of the class described, a frame equalizing bars and means for supporting said bars from said frame, a spring plank and means depending from said spring plank to rest pivotally on equalizing bars.

10. In a truck of the class described, a frame equalizing bars and means supporting said equalizing bars from said frame, a spring plank carried by said equalizing bars and saddles 18 fixed to said spring plank and riding on said equalizing bars.

11. In a truck of the class described, a bolster, equalizing bars, saddles riding thereon, and means permitting angular movement of the equalizing bars.

12. In a truck of the class described, a bolster, equalizing bars, saddles riding thereon, means permitting angular movement of the equalizing bars, and means for reducing the tendency of the bolster to swing transversely of the truck.

13. In a truck of the class described, a frame, pendent links rigidly connected therewith, springs supported by the links, a cross bolster, and means for pivotally supporting the bolster from said springs.

14. In a truck of the class described, equalizing bars, a saddle, and a spring plank, the saddle resting on the equalizing bars and the saddle and plank having interengaging parts.

15. In a truck of the class described, a top chord, a link bent to engage a plurality of sides of said chord and hang rigidly therefrom, each link near the lower edge of the chord being bent outwardly and downwardly, a spring seat supported on the lower ends of the link, a spring carried by the seat, and a cap on said spring having guiding lugs engaging the vertical parts of the link.

16. In a truck of the class described, a top chord, a link bent to engage a plurality of sides of said chord and hang rigidly there-

from, each link near the lower edge of the chord being bent outwardly and downwardly, a spring seat supported on the lower ends of the link, a spring carried by the seat, 5 a cap on said spring having guiding lugs engaging the vertical parts of the link, said cap having a journal bearing, and an equalizing bar having its ends received therein.

17. In a truck of the class described, a top 10 chord, a link bent to engage a plurality of sides of said chord and hang rigidly therefrom, each link near the lower edge of the chord being bent outwardly and downwardly, a spring seat supported on the lower 15 ends of the link, a spring carried by the seat, a cap on said spring having guiding lugs engaging the vertical parts of the link, said cap having a journal bearing, an equalizing bar having its ends received therein, said 20 equalizing bar having angle plates, and a saddle resting on the curved portion of the equalizing bar.

18. In a truck of the class described, an equalizing bar having a curved upper sur-

face at its center, a rectangular cross section 25 between its ends and center and a circular cross section at its ends, combined with angle plates secured adjacent the central portions of the equalizing bars and saddles resting on the circular curved portions of said 30 bars for contact with said angle plates.

19. In a truck of the class described, an equalizing bar having a curved upper surface at its center, a rectangular cross section 35 between its ends and center and a circular cross section at its ends, combined with angle plates secured adjacent the central portions of the equalizing bars, saddles resting on the circular curved portions of said bars for contact with said angle plates, and angle 40 metallic bars carried by said saddles.

Signed at the city and county of Philadelphia, State of Pennsylvania, this 23rd day of April, 1909.

WALTER S. ADAMS.
